DESIGN FOR A GAME DEVICE

Rene Vandenborre, New York, N. Y., assignor to Parker Brothers, Incorporated, Salem, Mass., a corporation of Maine

Application February 29, 1940, Serial No. 90,595

Term of patent 14 years

To all whom it may concern:

Be it known that I, Rene Vandenborre, a citizen of the United States of America, residing at New York, in the county and State of New York, have invented a new, original, and ornamental Design for a Game Device, of which the following is a specification, reference being had to the accompanying drawing, forming a part thereof.

The figure is a plan view of a game device
showing my new design.

The article is made of sheet material of no
substantial thickness.

I claim:

The ornamental design for a game device, substantially as shown and described.

RENE VANDENBORRE.
